Primary Examiner — Susan Moon Lee

CLAIM

The ornamental design for a scanner, as shown and described herein.

DESCRIPTION

FIG. 1 is a front elevation view of a scanner embodying our new design;

FIG. 2 is a rear elevation view of the embodiment of FIG. 1.

FIG. 3 is a right side view of the embodiment of FIG. 1.

FIG. 4 is a left side view of the embodiment of FIG. 1.

FIG. 5 is a top plan view of the embodiment of FIG. 1.

FIG. 6 is a bottom plan view of the embodiment of FIG. 1.

FIG. 7 is a top, front and right side perspective view of the embodiment of FIG. 1.

FIG. 8 is a top, front and right side perspective view of the embodiment of FIG. 1, when the cover is lifted; and,

FIG. 9 is a bottom, front, and right perspective view of the embodiment of FIG. 1.

Elements shown in broken lines are not claimed.

1 Claim, 9 Drawing Sheets
